UNITED STATES PATENT OFFICE.

JAMES T. COWLEY, OF SYRACUSE, NEW YORK.

POWER-CONTROL DEVICE.

Application filed April 8, 1925. Serial No. 21,719.

To all whom it may concern:

Be it known that I, JAMES T. COWLEY, a citizen of the United States of America, and resident of Syracuse, in the county of Onondaga and State of New York, have invented new and useful Improvements in Power-
Control Devices, of which the following is a specification.

This invention pertains to power controllers for pneumatic despatch systems and relates more particularly to automatically actuating controllers of the so-called minimum flow type of which the patent to Libby, 968,578, August 30, 1910, furnishes an early example.

Controllers of this type comprise essentially a valve, hereinafter referred to as the "main" valve, located between the transmission tube and an air exhauster or vacuum drum, such valve cutting off carrier propelling air flow through the tube when the tube is idle, although there is at all times a continuous flow of air through the transmission tube of relatively small volume, insufficient to propel a carrier, and known as the "minimum flow," and a pneumatic, for example a piston or diaphragm which responds either directly or indirectly to changes in pressure in the tube due to the momentary cutting off or checking of the minimum flow of air incident to the insertion of a carrier in the tube, and which by such response opens wide the main valve to permit a carrier propelling air current to flow through the transmission tube.

In the form of apparatus described in the Libby patent the period during which the valve remains open is determined solely by the operation of a timing device. The present invention is intended to improve the operation of devices of this general type by eliminating the timing device and in place thereof providing means which is responsive directly to the change of pressure in the transmission tube incident to discharge of the last carrier therefrom for initiating closure of the main controlling valve.

In the accompanying drawings a preferred embodiment of the invention is illustrated by way of example,

Fig. 1 being a diagrammatic elevation, partly in section, showing the improved con-

troller installed between one transmission tube of a pneumatic system and the exhaust header thereof.

Fig. 2 is a fragmentary vertical section to much larger scale, showing the interior construction of the controller, the parts being in normal position with the main valve closed;

Fig. 3 is a fragmentary section showing certain of the parts in the position which they occupy when the main valve is open and while the carrier is in flight through the tube;

Fig. 4 is a fragmentary section showing certain of the parts illustrated in Fig. 3 but occupying the position which they assume immediately upon delivery of the last carrier from the transmission tube and before the main valve has closed;

Fig. 5 is a fragmentary elevation, to somewhat larger scale than Fig. 1, showing the lower part of the controller with its casing broken away to illustrate the interior construction; and

Fig. 6 is a plan view of the controller to substantially the same scale as Fig. 2.

Referring to Figs. 1 and 5 of the drawings, the numeral 1 indicates a portion of a central station desk provided with the despatch terminal 2 forming a part of the sending transmission tube 3 leading to an outlying station. The corresponding return transmission tube 4 is provided with the usual normally closed delivery terminal 5 and with the extension tube 6 which passes down through the top of the desk 1 and is connected with the power control apparatus indicated generally by the numeral 7. A suction tube 8 leads from the power control apparatus to the usual suction drum or header 9 in which a vacuum or low pressure is maintained by means of a suitable exhauster not shown. A continuous air passage or conduit is thus provided extending from the terminal 2 to the exhaust, that portion of the conduit provided by tubes 3 and 4 forming the transmission line.

The power control apparatus 7 which forms the immediate subject matter of the present invention preferably comprises an elongate casing 10 (Figs. 1 and 5) having an opening in its side wall defined by flange 11 for the reception of the end of the tube ex-

tension 6. The lower end of this casing is also furnished with an opening defined by a flange 12 for the reception of the end of the suction tube 8.

5 The interior of the casing 10 is divided into an inlet chamber 13, communicating at all times with the transmission tube, and an outlet chamber 14, communicating freely with the suction tube 8, by a partition or 10 septum 15. Preferably this partition is of U-shape, comprising the substantially parallel spaced walls 17 and 18. These walls are furnished with coaxial valve orifices providing communication between the chambers 13 15 and 14. Normally these orifices are closed by means of the heads 19 and 20 respectively of a valve 21 of balanced type. While a 20 valve of this type is preferred, the particular form of valve employed is not essential to the present invention and it is contemplated that other types of valves, for example a valve having a single head cooperating with a single valve orifice, may be employed if desired.

25 As herein shown the tubes 6 and 8 are connected by means of a small pipe 6^a which permits a constant flow of air of small volume to be drawn through the transmission tube, such flow being known as the 30 "minimum flow." While it is preferred to employ this small pipe disposed outside of the casing 10, similar results may be secured by providing a small passage through the septum 15, or alternatively by permitting leakage past the valve heads.

35 The upper wall 10^a of the casing 10 is preferably provided with a removable section 22 (Fig. 3) for convenience in assemblage of the parts. This removable section 40 or cover is furnished with a central boss 23 having a guide passage for the stem 24 of the main valve 21. The upper wall 10^a of the casing is extended laterally and upwardly to provide the saucer shaped lower member 45 10^b of the main pneumatic motor casing. This bottom member 10^b terminates in a flange 25 forming a seat for the edges of a flexible diaphragm 26 which is clamped between the flange 25 and a flange 27 forming 50 the edge of a downwardly concave cover member 28. The cover member 28 and the bottom member 10^b may be connected by bolts 28^a or other suitable securing means.

55 The casing comprising the members 10^b and 28 is divided by the diaphragm 26 into upper end lower chambers 29 and 30 respectively. The chamber 30 is always in free communication with the outer atmosphere by means of a port or ports 31. A small 60 bleeder opening 42, preferably controlled by a needle valve 43, allows air at atmospheric pressure slowly to leak into the chamber 29 of the main motor.

65 The central part of the diaphragm 26 is preferably clamped between stiffener plates

32 and 33. These plates and the diaphragm are provided with central apertures for the passage of the reduced and screw threaded upper end 34 of the stem 24 of the main valve. A nut 35 engaging the member 34 70 clamps the plates 32 and 33 against the diaphragm.

An internally screw threaded sleeve 36 engages the upper end of the stem 24 above the nut 35 and constitutes a socket for the screw threaded lower end of a rod 37 which forms an extension of the stem 24. The rod 37 slides in a guide opening in the upper end of a hollow gland 38 having screw threaded engagement with an opening in a 80 boss 39 projecting from the upper surface of the cover 28. A coiled spring 40 surrounds the rod 37, having one of its ends bearing against the inner surface of the gland 38 and its other end bearing against 85 a radial flange 41 on the sleeve 36. This spring tends to depress the diaphragm 26 and thus to close the main valve, and its tension may be varied by turning the gland 38.

90 The cover 28 is provided with a large opening surrounded by an annular flange 44. A flange 45 projecting from the base member 46 of an auxiliary motor casing is secured to the flange 44. The base member 46 of the auxiliary motor casing is furnished with an upstanding cylindrical wall 56 terminating in a radial flange 57 which supports the outer edge of a flexible diaphragm 58. This diaphragm is clamped 100 between the flange 57 and a flange 59 projecting from the edge of the downwardly concave cover 60 of the auxiliary motor casing. The diaphragm 58 divides the auxiliary motor casing into upper and lower 105 chambers 61 and 62 respectively, the latter communicating freely with the atmosphere by means of a port 63.

A partition 64 extending across the base member 46 of the auxiliary motor casing forms the bottom of the chamber 62 and this partition 64 is furnished with a centrally disposed boss 65 having a guideway or passage for the reception of a sliding stem 66.

110 The central part of the diaphragm 58 of the auxiliary motor is clamped between stiffening plates 67 furnished with openings for the reception of the reduced, screw threaded upper end 68 of the stem 66. A nut 69 holds the stem, the plates 67, and the diaphragm 58 in assembled relation.

115 The cover member 60 of the auxiliary motor casing is furnished with a centrally disposed upstanding boss 70 provided with a 120 guide opening axially aligned with the stem 66. An abutment rod 71 slides freely in this guide opening. The upper end of the rod 71 is screw threaded for the reception of an adjustable stop nut which limits the 125 movement of the rod 71 in its guideway.

Normally the lower end of the abutment rod 71 is spaced from the upper end of the stem 66 as will hereinafter be described.

5 A yoke member 73 is mounted upon the upper end of the rod 71 and tension springs 74 and 75 are attached to its opposite ends by means of adjustable bolts 76 and 77 respectively. The lower ends of the springs 74 and 75 are attached to lugs 78 projecting 10 up from the cover 60.

The lower end of the stem 66 of the diaphragm 58 is somewhat reduced in diameter as indicated at 79 and upon this reduced portion of the stem an auxiliary valve disk 15 80 is mounted to slide. This valve disk is adapted to cooperate with an annular valve seat 81 to close a passage 82 leading from the chamber 29 of the main motor casing to a duct 83 communicating with the inlet 20 chamber 13 of the casing 10 and thus with the transmission tube.

The valve disk 80 is furnished with a sleeve 85 which slides freely upon the part 79 of the stem 66. The valve disk 80 is normally held against a stop member 86 carried by the stem by means of a coiled compression spring 87 whose lower end bears against a collar 88 secured to the lower end of the stem 66 by a nut 89.

30 The member 66 not only constitutes a stem for connecting the diaphragm 58 with the auxiliary valve 80, but it also itself forms a cut-off valve as hereinafter described. For this purpose the member 66 is provided 35 with an axial passage 94 opening at its lower end through the side of the stem at the point 95, and opening at the upper end of the stem at the point 96 into the upper chamber 61 of the auxiliary motor casing. 40 The member 66 is also furnished with a port 97 substantially midway of its length communicating with the passage 94 and adapted to register with a port or chamber 98 in the boss 65 which communicates by means of a 45 passage 99 with the upper chamber 29 of the main motor casing.

The operation of the device is substantially as follows, it being assumed that when the parts occupy the position shown in Fig. 50 2 there is no carrier in the transmission tube and a small or minimum flow of air is entering the terminal 2 and passing through the transmission line.

When a carrier is introduced into the 55 transmission line, either at the terminal 2 or at the outlying station, this minimum flow of air is cut off or diminished, and as the transmission tube is in communication, by means of the small pipe 6^a, with the suction drum, the pressure in the transmission tube gradually decreases until a point is reached such that the diaphragm 26 of the main motor responds and rises in opposition to its spring 40, thus opening the 60 main valve 21. When the pressure in the

70 system begins to diminish, due to the introduction of a carrier as just described, such lowered pressure is slowly transmitted to the upper chamber 61 of the auxiliary motor casing, but owing to the restricted character of the passage 94 the pressure in the chamber 61 is not diminished sufficiently to raise the diaphragm 58 and close the valve 80 until the diaphragm 26 has opened the 75 main valve.

As soon as the main valve opens a greatly decreased pressure is produced in the transmission tube and in the chamber 29 as well as in the passage 83. The pressure in the chamber 61 is now reduced with relative 80 rapidity and the diaphragm 58 rises, closing the auxiliary valve 80 and thus cutting off the upper chamber 29 of the main motor from the transmission tube. Air at atmospheric pressure leaking slowly in through 85 the orifice 42 would soon build up pressure in the chamber 29 sufficient to enable the spring 40 to depress the diaphragm and thus close the main valve, whether the carrier had been delivered from the transmission tube or not. This action is prevented by provision of the cut off valve 66.

90 When the auxiliary valve 80 engages the seat 81 the diaphragm 58 is permitted to rise still further by reason of the yielding connection furnished by spring 87 between the collar 88 and the valve 80. The diaphragm 58 thus continues to rise until the port 97 comes opposite to the port 98. When the parts assume this position as indicated in 95 Fig. 3 communication is re-established between the chamber 29 and the transmission tube through the passage 99, the ports 98 and 97 and the passage 94. As the passage 94 is of greater capacity than the valve restricted orifice 42, the vacuum is maintained 100 in the chamber 29 and the main valve remains open.

105 During the first portion of the upward movement of the diaphragm 58 its movement is opposed only by the weight of the stem 66 and the valve parts carried thereby so that the diaphragm rises quite freely. After the valve 80 is seated upon its seat 81 or substantially simultaneously with such action, the upper end of the stem 66 engages the abutment rod 71 so that the further upward movement of the diaphragm 58 is additionally opposed by springs 74 and 75.

110 During the flight of the carrier the relatively high vacuum of the transmission tube is sufficient to maintain the diaphragm 58 in the uppermost position of Fig. 3 against the load imposed by springs 74 and 75, but 115 when the last carrier emerges from the transmission tube and the pressure accordingly increases slightly, the springs 74 and 75 force the diaphragm 58 down until the stem 66 assumes the position shown in Fig. 120 125 130

4 wherein the port 97 is out of registry with the port 98 although the auxiliary valve 80 is still in engagement with its seat 81.

So long as the parts remain in this position the chamber 29 of the main motor casting is cut off entirely from the transmission tube and exhauster so that the pressure slowly builds up by leakage through the orifice 42 until the spring 40 is able to 10 depress the diaphragm 46, thus closing the main valve. As soon as the main valve closes, the pressure in the transmission tube increases very substantially and this increase in pressure being transmitted through 15 the passage 94 to chamber 61 of the auxiliary motor casing builds up pressure in the latter until the diaphragm 58 drops and restores the valve 80 to its normal open position, when the parts are ready for a 20 repetition of the foregoing series of operations.

While ordinarily the weight of the diaphragm 58 and the parts supported thereby is depended upon for returning it 25 to its normal position, it is contemplated that a light spring 91 may be provided to assist in restoring it to normal position if circumstances should indicate this to be necessary or desirable.

30 While one desirable arrangement of parts has been illustrated and described as exemplifying the invention, it is to be understood that the invention is not necessarily restricted to the exact arrangement herein disclosed but that various changes in 35 proportions of parts, as well as in the shapes and relative arrangement of the various elements constituting the mechanism, may be made without departing from the spirit 40 of the invention.

I claim:

1. Pneumatic despatch apparatus having a transmission tube, an exhauster connected therewith and a main valve for controlling the flow of air through the transmission tube, a minimum flow of air through the tube being permitted when the valve is in closed position, and a pneumatic motor for operating the main valve, said motor responding to slight drop in pressure in the transmission tube incident to insertion of a carrier in the tube to open the main valve, and means for determining subsequent pressure conditions in the main motor comprising 45 an auxiliary pneumatic responsive to pressure change in the transmission tube, and means actuatable thereby for cutting off communication between the main motor and the transmission tube when the main valve opens and for immediately re-establishing such communication, said auxiliary pneumatic subsequently responding to change in pressure in the transmission tube incident to delivery of the carrier therefrom again to 50 cut off such communication.

2. Pneumatic despatch apparatus having a transmission tube, an exhauster connected therewith and a main valve for controlling the flow of air through the transmission tube; a minimum flow of air through the tube being permitted when the valve is in closed position, and a pneumatic motor for operating the main valve, said motor having a chamber and a pair of passages either of which is adapted to connect the chamber 70 with the transmission tube, one at least of said passages normally being open, the motor responding to drop in pressure in the transmission tube due to cutting off of minimum flow by introduction of a carrier 80 to open the main valve, and means for determining subsequent pressure conditions in the motor chamber comprising a pair of auxiliary valves for controlling the respective passages, one of said valves closing one 85 of said passages when the main valve opens, the other passage being open during substantially the entire flight of the carrier, and the other valve also closing its passage when the last carrier emerges from the 90 transmission tube thereby completely to shut off the motor chamber from the transmission tube.

3. Pneumatic despatch apparatus having a transmission tube and a main valve for controlling the flow of air through the transmission tube, and a pneumatic motor for operating the main valve, said motor having a chamber and a pair of passages either of which is adapted to connect the chamber 95 with the transmission tube, one at least of said passages normally being open, the motor responding to change in pressure in the transmission tube to open the main valve, and means for determining subsequent pressure conditions in the motor chamber comprising an auxiliary pneumatic responsive to pressure change in the transmission tube, a pair of auxiliary valves actuatable by the auxiliary pneumatic for 100 controlling the respective passages, said pneumatic closing one of said valves when the main valve opens and immediately thereafter opening the other valve and holding it open during the flight of the carrier, 110 said auxiliary pneumatic responding to the slight change in pressure in the transmission tube incident to delivery of the last carrier therefrom to close said last named auxiliary valve.

4. Pneumatic despatch apparatus having a transmission tube, an exhauster connected therewith and a main valve for controlling the flow of air through the transmission tube, a minimum flow of air through the tube being permitted when the valve is in closed position, and a pneumatic motor for operating the main valve, said motor having a chamber normally communicating with the transmission tube by means of an open pas- 125 130

- sage, an auxiliary valve for closing said passage, means for closing the auxiliary valve when the main valve opens, and a cut-off valve normally closing a second passage between the motor chamber and transmission tube, said cut-off valve opening after the auxiliary valve closes. 5. Pneumatic despatch apparatus having a transmission tube, means for producing carrier propelling air flow in the tube, a main valve for controlling the flow of air through the transmission tube, and a pneumatic motor for operating the main valve, said motor having a chamber normally communicating with the transmission tube by means of an open passage, an auxiliary valve for closing said passage, a cut-off valve normally closing a second passage leading from the motor chamber to the transmission tube, and means responsive to pressure change in the transmission tube due to opening of the main valve for closing the auxiliary valve and opening the cut-off valve. 6. Pneumatic despatch apparatus having a transmission tube, an exhauster connected therewith and a main valve for controlling the flow of air through the transmission tube, a minimum flow of air through the tube being permitted when the valve is in closed position, and a pneumatic motor for operating the main valve, said motor having a chamber normally communicating with the transmission tube by means of an open passage, an auxiliary valve for closing said passage, a cut-off valve normally closing a second passage leading from the motor chamber to the transmission tube, and an auxiliary pneumatic motor responsive to pressure change in the transmission tube, said auxiliary motor closing the auxiliary valve and opening the cut-off valve immediately after the main valve opens and subsequently closing the cut-off valve while still keeping the auxiliary valve closed. 7. Pneumatic despatch apparatus having a transmission tube, means for creating carrier propelling air flow therein, and a main valve for controlling the flow of air through the transmission tube, and a pneumatic motor for operating the main valve, said motor having a chamber normally communicating with the transmission tube by means of an open passage, an auxiliary valve for closing said passage, an auxiliary pneumatic motor having a flexible diaphragm, a stem secured to the diaphragm, said stem constituting a cut-off valve normally closing a second passage leading from the valve chamber to the transmission tube, and means connecting the auxiliary valve to said stem. 8. Pneumatic despatch apparatus having a transmission tube, an exhauster connected therewith and a main valve for controlling the flow of air through the transmission tube, a minimum flow of air through the tube being permitted when the valve is in closed position, and a pneumatic motor for operating the main valve, said motor having a chamber normally communicating with the transmission tube by means of an open passage, an auxiliary valve for closing said passage, an auxiliary pneumatic responsive to pressure variation in the transmission tube, and means connecting the auxiliary pneumatic to the auxiliary valve, said connecting means being yieldable to permit relative movement of the pneumatic and valve. 9. Pneumatic despatch apparatus having a transmission tube, means for creating carrier impelling air flow therein and a main valve for controlling the flow of air through the transmission tube, and a pneumatic motor for operating the main valve, said motor having a chamber normally communicating with the transmission tube by means of an open passage, an auxiliary valve for closing said passage, a seat for said auxiliary valve, an auxiliary pneumatic responsive to pressure variation, and means connecting the auxiliary valve to the auxiliary pneumatic, said connecting means comprising a yieldable resilient part permitting the pneumatic to move independently of the valve while the latter engages the seat. 10. Pneumatic despatch apparatus having a transmission tube, an exhauster connected therewith and a main valve for controlling the flow of air through the transmission tube, a minimum flow of air through the tube being permitted when the valve is in closed position, and a pneumatic motor for operating the main valve, said motor having a chamber and a passage for transmitting transmission tube pressure to said chamber, a normally closed valve controlling said passage, and an auxiliary pneumatic for opening said valve during the flight of a carrier through the transmission tube. 11. Pneumatic despatch apparatus having a transmission tube, means for creating carrier impelling air flow therein, and a main valve for controlling the flow of air through the transmission tube, and a pneumatic motor for operating the main valve, said motor having a chamber and a passage for transmitting transmission tube pressure to said chamber, a normally closed valve controlling said passage, and an auxiliary pneumatic responsive to pressure change in the transmission tube to hold said normally closed valve open during flight of a carrier through the transmission tube and to permit said valve to close when the last carrier emerges from the tube. 12. Pneumatic despatch apparatus having a transmission tube, an exhauster connected therewith and a main valve for controlling the flow of air through the transmission tube, a minimum flow of air through the tube be-

ing permitted when the valve is in closed position, and a pneumatic motor for operating the main valve, said motor having a chamber normally communicating with the 5 transmission tube by means of an open passage, an auxiliary valve for closing said passage, an auxiliary motor comprising a flexible diaphragm having a stem, said stem passing through an opening in the auxiliary 10 valve, and spaced stop elements permitting limited relative movement of the stem and valve.

13. Pneumatic despatch apparatus having a transmission tube, means for creating carrier impelling air flow therein, and a main valve for controlling the flow of air through the transmission tube, and a pneumatic motor for operating the main valve, said motor having a chamber normally communicating 20 with the transmission tube by means of an open passage, an auxiliary valve for closing said passage, an auxiliary motor comprising a flexible diaphragm having a stem, one end of the stem sliding freely in a central opening 25 in the auxiliary valve, a stop element carried by the stem, and a coil spring encircling the stem and normally holding the valve against the stop element.

14. Pneumatic despatch apparatus having 30 a transmission tube, an exhauster connected therewith and a main valve for controlling the flow of air through the transmission tube, a minimum flow of air through the tube being permitted when the valve is in closed 35 position, and a pneumatic motor for operating the main valve, said motor having a chamber and two passages providing communication between the chamber and the transmission tube, and valve means for controlling said passages, said valve means closing one passage and opening the other upon opening of the main valve responsive to insertion of a carrier into the transmission tube and closing both passages when the last 45 carrier emerges from the tube.

15. Pneumatic despatch apparatus having a transmission tube, means for creating a carrier impelling air flow therein, and a main valve for controlling the flow of air 50 through the transmission tube, and a pneumatic motor for operating the main valve, said motor having a chamber and a pair of passages for admitting transmission tube pressure to said chamber, valves for controlling the respective passages, an auxiliary 55 pneumatic responsive to drop in pressure in the transmission tube for closing one of said valves and responsive to continued low pressure in said tube to open the other valve, 60 said pneumatic responding to subsequent slight increase in pressure in the tube to close the latter valve without opening the first valve.

16. Power control apparatus for a pneumatic despatch system comprising a pneu-

matic motor having a flexible diaphragm provided with a stem, a valve carried by the stem, a movable abutment normally spaced from but engageable by the stem, and resilient means tending to retain said abutment 70 in normal position.

17. Power control apparatus for a pneumatic despatch system comprising a pneumatic motor having a flexible diaphragm provided with a stem, a slideable abutment 75 spaced from but engageable by the stem as the diaphragm moves in one direction, a yoke secured to the abutment, and springs engaging the opposite ends of the yoke and tending to retain the abutment in normal 80 position.

18. Pneumatic despatch apparatus having a transmission tube, an exhauster connected therewith and a main valve for controlling the flow of air through the transmission 85 tube, a minimum flow of air through the tube being permitted when the valve is in closed position, and a pneumatic motor for operating the main valve, said motor having a chamber and two passages for admitting 90 transmission tube pressure to the chamber, an auxiliary motor having a flexible diaphragm, a stem secured to the diaphragm, said stem constituting a valve for controlling one of said passages, and an auxiliary 95 valve mounted upon the stem for controlling the other passage.

19. Pneumatic despatch apparatus having a transmission tube, an exhauster connected therewith and a main valve for controlling 100 the flow of air through the transmission tube, a minimum flow of air through the tube being permitted when the valve is in closed position, and a pneumatic motor for operating the main valve, said motor having a chamber and two passages for admitting 105 transmission tube pressure to the chamber, an auxiliary motor having a flexible diaphragm, a stem secured to the diaphragm, said stem having an axial passage and a port 110 opening through its side and constituting a valve for controlling one of said passages, and a valve disk mounted upon the stem for controlling the other passage.

20. Pneumatic despatch apparatus having 115 a transmission tube, an exhauster connected therewith and a main valve for controlling the flow of air through the transmission tube, a minimum flow of air through the tube being permitted when the valve is in closed position, and a pneumatic motor for operating the main valve, said motor having a chamber and two passages for admitting 120 transmission tube pressure to the chamber, an auxiliary pneumatic motor having a chamber closed at one side by an auxiliary diaphragm, a stem secured to the diaphragm having an axial passage opening into said chamber of the auxiliary motor, the stem 125 also having ports in its sides and constitut-

ing a valve for controlling one of said passages, and a valve actuatable by the stem for controlling the other passage.

21. Pneumatic despatch apparatus having a transmission tube, and a main valve for controlling the flow of air through the transmission tube, and a pneumatic motor for operating the main valve, said motor having a chamber normally communicating with the 10 transmission tube by means of an open pas-

sage, an auxiliary valve for closing said passage, means for closing the auxiliary valve when the main valve opens, and means operative subsequently to the closure of the auxiliary valve for opening communication 15 through another passage between the motor chamber and the transmission tube.

Signed by me at Syracuse, New York, this 25th day of March 1925.

JAMES T. COWLEY.
